UNITED STATES PATENT OFFICE

159,960

HOLDER FOR VACUUM CLEANERS OF THE TANK OR CYLINDER TYPE

Jack B. Davey, Kenmore, N. Y.

Application March 4, 1949, Serial No. 1,223

Term of patent 14 years

(Cl. D14—3)

To all whom it may concern:

Be it known that I, Jack B. Davey, a citizen of the United States, residing at Kenmore, in the county of Erie and State of New York, have invented a new, original, and ornamental Design for Holder for Vacuum Cleaners of the Tank or Cylinder Type, of which the following is a specification, reference being had to the accompanying drawing, forming part thereof.

Fig. 1 is a perspective view of a holder, showing my design, the handle of the holder being shown broken away for purposes of illustration and to show additional length to conform to the length of the handle shown in other figures of the drawing.

Fig. 2 is a side elevation on a reduced scale looking at the same from the left.

Fig. 3 is a side elevation looking at the same from the right.

Fig. 4 is a rear elevation of the holder.

Fig. 5 is a top plan view of the same.

I claim:

The ornamental design for a holder for vacuum cleaners of the tank or cylinder type, as shown.

JACK B. DAVEY.
